US00D992508S

(12) **United States Design Patent** (10) **Patent No.:** **US D992,508 S**
Sun (45) **Date of Patent:** **** Jul. 18, 2023**

(54) **PAPER SHREDDER**

(71) Applicant: **DONGGUAN SUNTECH ELECTRONICS CO., LTD.,**
 Dongguan (CN)

(72) Inventor: **Yicheng Sun**, Dongguan (CN)

(73) Assignee: **DONGGUAN SUNTECH ELECTRONICS CO., LTD.,**
 Dongguan (CN)

(**) Term: **15 Years**

(21) Appl. No.: **29/790,522**

(22) Filed: **Dec. 2, 2021**

(30) **Foreign Application Priority Data**

Nov. 24, 2021 (EM) 008772156-0001

(51) **LOC (14) Cl.** **18-04**
